TO MARGARET C. CONDIT, OF NORTH STOUGHTON, MASSACHUSETTS.

ENGINE-PRIMER.

1,260,091.

Specification of Letters Patent. Patented Mar. 19, 1918.

Application filed May 19, 1917. Serial No. 169,720.

To all whom it may concern:

Be it known that I, BERNARD B. STUBBLEFIELD, a citizen of the United States, residing at Boston, in the county of Suffolk 5 and State of Massachusetts, have invented new and useful Improvements in Engine-Primers, of which the following is a specification.

This invention relates to engine primers 10 and particularly devices for priming all kinds of internal combustion engines including those used in connection with automobiles, marine vessels, the device being also applicable to stationary engines of the 15 internal combustion type.

The object of the invention is to produce 20 simple, economical and effective priming means operable by a single stroke of a manually controlled pump which, in automobile practice, is arranged for operation upon the dash or instrument board of the vehicle, whereby the operator may prime all of the cylinders of the engine without leaving his seat.

25 One of the principal objects of the present invention is to provide in connection with each cylinder of an internal combustion engine, a priming unit embodying valve mechanism and a priming liquid expressing 30 member, both operable under the influence of the priming liquid under pressure caused by the operation of the pump, the arrangement being such that the valve is charged with priming liquid, shifted to its discharging 35 position, and the expressing member operated simultaneously for forcing the priming liquid into the respective engine cylinder, all of the parts being restored to their initial positions automatically when 40 the operation of the pump is terminated.

With the above and other objects in view, the invention consists in the novel construction, combination and arrangement of parts, herein described, illustrated and claimed.

45 In the accompanying drawings:-

Figure 1 is a fragmentary vertical longitudinal section through sufficient of an automobile to illustrate the priming apparatus in its applied relation thereto.

50 Fig. 2 is an enlarged sectional view of the pump and the reservoir.

Fig. 3 is an enlarged diametrical section through one of the priming units, showing the relation thereof to one of the cylinders 55 of the engine.

Fig. 4 is a section on the line 4—4 of Fig. 3.

Fig. 5 is a view looking toward one end of Fig. 3 with the adjacent head removed.

Fig. 6 is a view similar to Fig. 3 showing 60 a modification in the form and arrangement of the valve and expressing piston.

Fig. 7 is a view showing another modified form of the engine primer.

Referring to the drawings A designates 65 generally an internal combustion engine embodying cylinders 1, 2, 3 and 4, and 5 represents the dash or instrument board of an automobile or motor truck.

In conjunction with each cylinder of the 70 engine, I employ a priming nipple 5 the central bore 6 of which is in direct and constant communication with the interior of the cylinder and the outer end of which is counterbored and internally threaded as 75 shown at 7 to receive a back pressure check valve casing 8 which is screwed into the counterbore 4 and which contains a back pressure check valve 9 co-operating with a seat 10 against which it is yieldingly held 80 by means of a contractile spring 11 having one end attached to the valve and the other end secured to a fixed point within the central bore 12 of the valve casing 8.

In connection with each cylinder, I employ 85 a priming unit which itself embodies a barrel or cylinder 13 having a threaded socket 14 therein which receives the threaded end portion 15 of the valve casing 8. The parts 5, 8 and 13 are thus separately 90 connected together but bear a fixed relation to each other.

The cylinder 13 has the opposite ends thereof threaded to receive internally threaded caps or heads 16 and 17. The head 95 17 has connected thereto the discharge end of a service pipe 18 leading to a source of supply for the priming liquid hereinafter particularly described, the priming liquid being fed to the interior of the cylinder 13 100 by means of said pipe 18. Mounted to reciprocate in the cylinder 13 is a piston valve 19 of hollow cylindrical formation but provided between the ends thereof with an imperforate head or partition 20. Mounted to 105 reciprocate within the valve 19 is an expressing piston 21, the outward movement of which is limited by means of a stop 22 shown in the form of a screw which is threaded diametrically through one end of 110

the reciprocatory piston valve 19. The piston 20 is yieldingly pressed toward and against the stop 22 by means of an expansion spring 23 one extremity of which is inserted in a socket 24 in the center of the piston 21, the other extremity of the spring being inserted in a central socket 25 in the partition or head 20. The piston valve 19 is held toward the head 17 of the cylinder 13 by means of a coiled expansion spring 26 one extremity of which is inserted in a central socket 27 in the partition or head 20, while the opposite extremity of said spring is inserted in a socket 28 in the extremity of 15 a tensioning screw 29, the latter being threaded through a central opening 30 in the cap or head 16 and being provided with a milled head 21, the screw 29 being held when adjusted by means of a jam nut 32.

20 The piston valve 19 is formed in line with one side of the head 20 with an external annular groove 33 intersected by ports 34 which place said groove 33 in communication with the chamber 35 in which the piston 21 operates. The wall of the cylinder 13 is formed with a by-pass 36 which leads from a priming liquid chamber or cavity 37 in the head 17 to the annular groove 33. This enables the priming liquid to be forced 25 through the ports 34 into the chamber 35 from which it is subsequently expressed by means of the piston 21.

25 The service or feed pipe 18 communicates at its receiving end with a reservoir 38 which is shown as provided with attaching lugs 39 by means of which it may be screwed to the dash or instrument board 5. The reservoir 38 is provided with a filling cap 40 to enable the priming liquid, usually gasolene, to 40 be introduced therein. 41 designates a pump barrel which is set at an inclination and a portion of which is contained within the reservoir 38, another portion thereof extending beyond the reservoir 38 so as to pass 45 through an opening in the dash or instrument board 5. Mounted within the barrel 41 is a reciprocatory plunger head or piston 42 fixedly carried by an operating stem or plunger rod 43, the latter extending through 50 the head 44 of the barrel 41 and being provided with a hand grip or handle 45 within reach of the operator in his seat. A spring 46 surrounds the pump rod 43 and serves to hold the plunger head 42 at the inner limit 55 of its stroke. The barrel 41 is equipped with a spring pressed foot or admission valve 47 at the lower end thereof, said valve being held normally open by the action of the spring 48 by which it is carried, said valve 60 47 closing automatically during the working stroke of the pump. The barrel 41 is also provided with a vent hole 49 located in the upper part of the reservoir 38 above the normal level of the priming liquid therein. The 65 service pipe 18 communicates directly with

the discharge end of the pump barrel 41. The service pipe 18 has incorporated therein a stop cock 50 and each of the nipples 5 is also preferably equipped with a stop cock 51. This enables the flow of priming liquid to 70 be cut off when it becomes necessary to make repairs at different points in the priming apparatus. The service pipe 18 is provided with branches 18' leading to the cylinders 13 of the priming units. 75

In order to prime the cylinders of the engine it is only necessary to give one or more strokes to the pump which as described and shown is within reach of the operator while in his seat. In each working 80 stroke of the pump, the foot valve 47 automatically closes, and pressure is put behind the priming liquid in the service pipe 18, the branches 18' thereof, and in the cavity or chamber 37 of the head 17 of each priming cylinder 13. This pressure produces a working stroke of the expressing piston 21 and at the same time shifts the piston valve 19 so that the annular groove 33 moves out of registry with the by-pass 36 and into line 90 with a port 53 in the cylinder 13 which communicates directly with the valve casing 8. The priming liquid is thus forced into the adjacent cylinder of the engine and immediately thereafter, the piston valve 19 is returned to the position illustrated in Fig. 3 by the action of the spring 26, the piston 21 being returned to its initial position by means of the spring 23. In each working 95 stroke of the pump, the operation above described takes place. The check valve 9 prevents the return of the priming liquid and also seals the bore 6 of the nipple 5 so as to prevent any flame from reaching the cylinder 13. 100

105 In lieu of the arrangement of the piston valve and expressing piston shown in the preceding figures, the arrangement illustrated in Fig. 6 may be employed if so desired. Under the arrangement shown in Fig. 6, the piston valve 19' is provided with a guiding stem 54 extending therefrom toward the head 17 of the cylinder 13, and the expressing piston 21' is slidably mounted upon the stem 54, being formed with a central bore 55 to receive said stem. The piston 21' is held from escaping from the end of the stem 54 by means of a stop 56 shown in the form of a screw which is threaded into the extremity of the stem 54. A spring 57 115 is coiled around the stem 54, bearing at one end against the piston 21' and having its other end received in an annular recess 58 in the head 20' of the piston valve 19'. The operation of the piston valve 19' and the expressing piston 21' is the same as that previously described in connection with the piston valve 19 and the expressing piston 21. 120

125 Under the arrangement illustrated in Fig. 7, the priming cylinder 60 is arranged verti-

cally, the valve 61 is arranged slidable therein in the same manner as in the preceding figures, and the expression piston 62 being mounted for sliding movement in the chamber 68 of the valve. The lower end of the cylinder 60 is closed by means of a removable threaded plug 64 while the opposite end of the cylinder is closed by a threaded plug 65 comprising an air chamber 66 having a 10 port 67, which leads into the chamber 68 of the cylinder 60 into which the valve 61 works. The air chamber 66 prevents the formation of an air cushion behind the valve 61 which would interfere with the free operation of said valve. The return spring 69 for the valve 61, has one extremity thereof attached to the plug 65 as shown.

The cylinder 60 is formed in the wall thereof with a cylindrical bore 70 terminating at its inner end in a taper or conical valve seat 71 in conjunction with which operates a check valve 72, a portion of which is cylindrical, and a portion of which is tapered or conical as shown to fit the valve 25 seat 21. The valve may be accurately ground to its seat by reason of the tapered formation of the inner end thereof. The outer end of the bore 70 is normally closed and tightly sealed by means of a threaded plug 73. A 30 spring 74 is confined between the plug 72 and yieldingly holds said valve against its seat. A port 75 extends from the chamber 68 to the valve seat 71. Another port 76 intersects the valve seat 71 and communicates with a passage 77 which leads to a three-way valve casing 78 in which is mounted a three-way valve 79 having an operating handle 80. The valve 79 is of the tapered plug type and comprises a single port 40. The casing 78 comprises an inlet port 82, a priming outlet port 83, a drain port 84 and a compression relief port 85. The valve 79 may be turned to any one of three positions, one position allowing the priming 45 liquid to pass directly to the engine, another position relieving the compression in the engine, and another position permitting the priming liquid to be drained from the passage 77. The chamber formed by the bore 50 70 acts as an air cushion chamber, the air compressed therein by the movement of the valve 72, assisting the spring 74 to return said valve to its seat.

Instead of using a pump as hereinabove 55 described, compressed air from any suitable source may be utilized to force the priming liquid under the necessary pressure into the priming cylinder.

I claim:—

60 1. The combination with the cylinder of an internal combustion engine, of a priming unit in communication therewith and embodying a cylinder, a reservoir for the priming agent, a feed pipe leading from 65 said reservoir to the cylinder of said prim-

ing unit, a piston valve mounted to reciprocate in the cylinder of the priming unit and having a cylindrical chamber to receive the priming agent and also formed with ports leading to and from said chamber, an auxiliary piston mounted for movement in said chamber, and means for forcing the priming agent under pressure through said feed pipe into the cylinder of the priming unit, said piston valve and auxiliary piston being operable by said liquid under pressure. 70 75

2. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe 80 into the cylinder of the priming unit, said piston valve and auxiliary piston being operable by said liquid under pressure, and a back pressure check valve between the engine cylinder and the cylinder of the priming 85 90 95 unit.

3. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe 100 into the cylinder of the priming unit, said piston valve and auxiliary piston being operable by said liquid under pressure, and a back pressure check valve between the engine cylinder and the cylinder of the priming 105 110 115 unit.

4. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe 120 125 130 into the cylinder of the priming unit, said piston valve and auxiliary piston being operable by said liquid under pressure, and yieldable means for effecting a return stroke of said piston valve.

piston valve and auxiliary piston being operable by said liquid under pressure, and yieldable means for effecting a return stroke of said auxiliary piston.

5. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe into the cylinder of the priming unit, said piston valve and auxiliary piston being operable by said liquid under pressure, and yieldable means for effecting the return strokes of said piston valve and said auxiliary piston.
- 10 25 30 35 40 45 50 55 60 65 70
6. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe into the cylinder of the priming unit, said piston valve and auxiliary piston being operable by said liquid under pressure, the chamber in which the auxiliary piston works being open at one end, and a piston stop extending across the open end of said chamber.

agent under pressure through said feed pipe into the cylinder of the priming unit, said piston valve and auxiliary piston being operable by said liquid under pressure, the cylinder of said priming unit being formed with a by-pass to lead the priming agent to said annular groove of the piston valve, and the cylinder of said priming unit being further formed with an outlet port located out of line with the discharge end of said by-pass and with which said annular groove of the piston valve is adapted to register at the limit of its working stroke.

7. The combination with the cylinder of an internal combustion engine, of a priming unit in communication therewith and embodying a cylinder, a reservoir for the priming agent, a feed pipe leading from said reservoir to the cylinder of said priming unit, a piston valve mounted to reciprocate in the cylinder of the priming unit and having a cylindrical chamber to receive the priming agent and also formed with ports leading to and from said chamber, an auxiliary piston mounted for movement in said chamber, means for forcing the priming agent under pressure through said feed pipe into the cylinder of the priming unit, said piston valve and auxiliary piston being operable by said liquid under pressure, the chamber in which the auxiliary piston works being open at one end, and a piston stop extending across the open end of said chamber.

In testimony whereof I affix my signature.

BERNARD B. STUBBLEFIELD.
